UNITED STATES PATENT OFFICE.

JOHN BEDFORD, OF ROSSVILLE, TENNESSEE.

DESIGN FOR A HOE.

SPECIFICATION forming part of Design No. 32,448, dated April 3, 1900.

Application filed January 31, 1900. Serial No. 3,527. Term of patent 14 years.

To all whom it may concern:

Be it known that I, JOHN BEDFORD, a citizen of the United States, residing at Rossville, in the county of Fayette and State of Tennessee, 5 have invented and produced a new and original Design for a Hoe, of which the following is a specification.

The invention relates to a new and original design for a hoe; and it has for its object to 10 provide a design of this character which will be both ornamental and useful.

The essential feature of the design resides in a hoe consisting of a blade tapering from its rear end to its front end and sigmoidally 15 curved from one end to the other, and a handle provided with reversely curved shanks extending longitudinally of the center of the blade and conforming to the configuration of the same, the front shank presenting an inner concave face and the rear shank presenting 20 a convex face to the blade.

In the drawings, Figure 1 is a perspective view of a hoe, showing my new and original design. Fig. 2 is a plan view. Fig. 3 is a 25 side elevation.

Referring to the drawings, 1 designates a tapering blade having straight converging

side edges 2 and provided with straight end edges 3 and 4, the edge 3 being shorter than the opposite end edge 4, as clearly shown in 30 Figs. 1 and 2. The blade 1 is sigmoidally curved, and the handle 5 is connected with the blade by shanks 6 and 7, diverging and reversely curved to agree with the curvature of the adjacent portions of the blade. The 35 shank 6 presents an inner rounded convex face to agree with the concave face of the adjacent portion 8 of the blade, and the other shank 7 presents an inner concave face to agree with the convex face of the portion 9 40 of the blade. The length of the blade is much greater than its width, and the diverging shanks of the handle extend longitudinally of the blade and are reversely curved, as shown.

What is claimed is—

The design for a hoe, as herein shown and described.

In testimony that I claim the foregoing as my own I have hereto affixed my signature in the presence of two witnesses.

JOHN BEDFORD.
